UNITED STATES PATENT OFFICE.

GEORGE N. KINNELL, OF PITTSFIELD, MASSACHUSETTS, ASSIGNOR OF ONE-THIRD TO
JOHN J. WHITTLESEY, OF PITTSFIELD, MASSACHUSETTS.

MIXING AND GRINDING MACHINE.

1,001,652.

Specification of Letters Patent. Patented Aug. 29, 1911.

Application filed June 23, 1909. Serial No. 503,813.

To all whom it may concern:

Be it known that I, GEORGE N. KINNELL, a citizen of the United States, residing at Pittsfield, in the county of Berkshire and 5 State of Massachusetts, have invented certain new and useful Improvements in Mixing and Grinding Machines for Concrete and other Substances, of which the following is a specification.

10 My invention relates to machines adapted for mixing concrete, cement, mortar and other compounds in a wet or dry state, and also to machines adapted to grind, as well as mix, friable materials or substances into 15 a comminuted mass.

The principal object of the invention concerns the combination with a rotary receptacle, of improved means for facilitating the process of mixing or grinding substances 20 and comprising a plurality of flexibly connected or jointed elements movable relatively to the receptacle and formed, arranged and operated in a novel manner. The quality of flexibility of the means re- 25 ferred to operates to break up lumpy or agglutinated parts or particles of the mass and to prevent the same from adhering together or to the walls of the receptacle or receiver, as commonly occurs in present 30 forms of mixers or grinders.

Having thus described the general character and purpose of my invention, I will proceed to describe a specific useful form of embodiment thereof in connection with 35 the accompanying drawings, wherein—

Figure 1 is a sectional side view of a mixing machine embodying the principles of my invention; Fig. 2 is a longitudinal sectional top view of the receiver or drum and 40 inclosed mechanism; Fig. 3 is a vertical sectional view of the same; Fig. 4 is an end view of the parts shown in Fig. 1, as seen from the rear or receiving end; Fig. 5 is a reduced cross-sectional view of the receiver or drum on the line *a—b* of Fig. 2, disclosing the interior mechanism, and Figs. 45 6 and 7, edge and top views, respectively, of the agitators attached to some of the chains.

50 The mixing receptacle is shown as a longitudinally extended cylinder, tube, or drum 1 rotatively supported at either end upon pillow-blocks 2, 3, each of which is provided with a set of antifriction-rolls 4, 4, 55 which engage annular tracks or ways 5, 5,

on the drum and serve as roller-bearings for the latter. The drum is preferably supported in a normally tilted position, being inclined downward from its rear or receiving end sufficiently to cause the mixture to 60 gravitate slowly toward the forward or discharging end. Forward or rearward displacement of the drum is prevented by the engagement of the rolls 4, 4, with annular flanges 6, 6, provided at either end of the 65 drum at the outer edges of the tracks or ways 5, 5.

The drum is operated by a rotary driven-shaft 7 supported in a position parallel to the axis of the drum preferably by the pillow-blocks 2, 3, the shaft being provided with pinions 8, 8, which are arranged to mesh with separate annular racks or ring-gear 9, 9, on the drum. As a convenient mode of driving the shaft 7, I have shown a 70 motor 10 with suitable power-transmitting connection, such as a gear-wheel 11 mounted on the motor-shaft and meshing with a gear-wheel 12 carried by the shaft 7.

The drum when employed essentially as a mixing receptacle, as here shown, is constructed with open ends, the receiving end being preferably slightly tapered at 13 to facilitate the collection of the substances introduced therat for mixture. Within the 80 drum are provided a plurality of flexibly connected or jointed elements adapted to play about in free relation thereto and within the mass to be mixed. These I have embodied in the form of chains or catenations 14, 15, composed of links movable relatively to each other and preferably hung upon rods or shafts 16, 17, and depending downward upon or to points adjacent the bottom of the drum in such manner as to 85 freely commingle with the mass to be mixed. Supposing the drum to move in a clock-wise direction, the several chains are shown as supported from points at the right of the axis of the drum looking forwardly and 90 somewhat above a horizontal plane through the axis, thus permitting a more extensive field for play when carried toward the opposite side by the centrifugal movement imparted to the mass by the action of the 95 drum.

The rotary shaft 16 and the stationary rod 17 are supported in spaced relation to each other and parallel to the axis of the drum preferably by uprights or standards 18, 19,

mounted upon a base 20, which may also serve as a support for the pillow-blocks 2, 3, and motor 10, at opposite ends of the drum, said shaft and rod being projected 5 freely through the body of the drum.

The chains 14, distributed at intervals along the shaft 16, are preferably arranged in pairs and united at the bottoms in the form of festoons, the upper ends being flexibly attached to rings 21 hung loose upon grooved eccentrics 22, which are keyed to the shaft and arranged in such a manner that alternate chains are raised by the eccentrics while the remaining half are lowered, thus imparting a see-saw movement to each festoon. I further provide at a point near the lower end of each of the chains 14 an agitator 23, provided with a plurality of radial members and having eyes for engagement with the adjacent links of the chain and forming a part thereof. The shaft 16 is rotated preferably by means of the shaft 7 with suitable power-transmitting connection, such as an endless link belt 24 engaging separate sprocket wheels 25, 26, carried by the said shafts at points beyond the body of the drum.

On the rod 17, which is preferably disposed in comparatively close proximity to 30 the wall of the drum, I arrange the chains 15, 15, opposite points intermediate adjacent festoons on the shaft 16, whereby the extended ends of the chains 15, which move loosely about on the bottom of the drum and 35 are carried forward by the action of the latter, play between the adjacent festoons and are less liable to become entangled therewith. Said chains 15, 15, are shown as flexibly secured to the rod 17 by means of 40 eye bolts 27, 27.

Supported by the pillow-block 18 is shown a hopper 28 projecting into the receiving end of the drum and adapted to direct the materials introduced for mixture, while at 45 the discharging end is shown a chute 29 supported by the pillow-block 19 in a suitable position to guide the discharged mixture. Said hopper and chute may be fixed to their respective supports or adjustably secured so as to vary their positions.

For the purpose of introducing water into the drum I have shown a pipe 30 journaled, or otherwise supported, on the pillow-block 18 at the receiving end and projecting 55 into the drum for discharge preferably at a point intermediate the receiving and discharging ends thereof so that the process of mixing the materials will have been partially performed before the addition of the 60 water. Said pipe is adapted to be connected at its outer end with any convenient source of supply and is provided with a valve 31 for regulating the quantity of water to be used.

65 The form of mixing receptacle herein

shown is adapted more particularly for the manufacture of concrete, cement or mortar on a large scale as would be required in the construction of extensive building foundations, dams, bridges, canals, etc. The normally inclined position of the drum and the unobstructed discharge end enable the force of gravity to automatically carry forward and discharge without manual intervention or assistance the finished mixture. The 75 process of mixing may proceed, therefore, without cessation or interruption, and, by the provision of additional means for automatically feeding materials to the hopper and for carrying off the completed mixture, 80 is independent of manual aid.

The free ends of the chains 15, 15, are carried along the bottom of the drum by the rotary motion imparted to the mass and tend to break up and grind agglutinated particles in the mixture and at the same time to free the sides of the drum from portions of the mass adhering thereto. The movement of the drum normally carries the mixed mass toward one side and away from the 90 chains 14, 15, and by tending to raise the center of gravity thereof causes the mass to fall backward upon the chains 14 and the agitators 23 provided thereon, which lift and knead the mass about by reason of the 95 vertical movements imparted thereto by the eccentrics on the rotary shaft 16.

I claim as new, and desire to secure by Letters Patent, the following:

1. A mixing machine comprising a receiving-chamber having an open receiving and an open discharging end, a rotary shaft projecting through said chamber and having an eccentric member fixed thereon, a catenation of movably connected links movably secured to said eccentric member and depending into said chamber and adapted to be actuated by said shaft. 100

2. A mixing or grinding machine comprising a receiving-chamber, a rotary shaft 110 within said chamber, a plurality of eccentric members fixed on said shaft, and a plurality of catenations composed of movably connected links depending from said shaft into said chamber and adapted to be actuated vertically by said shaft, each of said catenations having one end movably secured to a separate eccentric member and having its lower end connected with the corresponding end of an adjacent catenation to form a festoon, substantially as shown. 115

3. In a mixing machine, the combination with a receiving-chamber, a rotary shaft within said chamber, an eccentric member fixed on the shaft, and a catenation of movably connected links movably secured to said eccentric member and depending into said chamber in such manner as to commingle with the mass to be mixed and to agitate the same when actuated by the shaft, of aux. 125 130

iliary means provided on said catenation for lifting the mass, substantially as shown.

4. In a mixing or grinding machine, the combination with a receiving-chamber, of a support, a catenation of movably connected members secured to said support and having a free portion depending into said chamber, and means for imparting to said catenation movements alternately in an upward and downward direction for the purpose set forth.

5. In a mixing or grinding machine, the combination with a receiving-chamber, of a plurality of catenations depending into said chamber, means for the support of said catenations in a spaced relation, and means for imparting to adjacent catenations movements in opposite vertical directions.

6. In a mixing or grinding machine, the combination with a rotary receiving-chamber, of a catenation composed of a plurality of movably connected links depending into said chamber, means for the support of said catenation independently of said chamber, and means for imparting to said catenation a vibratory movement.

7. In a mixing or grinding machine, the combination with a receiving-chamber, of a support, a catenation composed of flexibly

connected members having its ends secured to spaced relation to said support and depending into said chamber, and means for imparting to said catenation a reciprocating vertical movement.

8. Apparatus of the class described comprising a receiving-chamber, a rotary shaft supported in an elevated position above the bottom of the chamber, a catenation of movably connected members secured to the shaft and depending into the chamber, and means formed or provided on the shaft whereby a reciprocating movement is imparted to said catenation.

9. A mixing and grinding machine comprising a receiving-chamber, a rotary shaft projecting into the chamber, a catenation of movably connected members secured to the shaft and having a free portion depending into the chamber, and eccentric means provided on the shaft for imparting a reciprocating vertical movement to said catenation.

In testimony whereof I hereunto affix my signature in presence of two witnesses.

GEORGE N. KINNELL.
